UNITED STATES PATENT OFFICE

JAMES LAWRENCE AUBLE, OF CINCINNATI, OHIO, ASSIGNOR TO M. & A. INC., OF CINCINNATI, OHIO, A CORPORATION OF OHIO

APPARATUS FOR FORMING SHEET METAL FORMS

Application filed November 27, 1931. Serial No. 577,467.

My invention relates to the art of drawing and forming sheet metal into forms by a series of forming operations without removing the piece being formed from the drawing and forming means.

It is an object of my invention to provide a drawing and forming device for forming sheet metal into various forms by continued movement in one direction while the various parts constituting the forming device automatically adjust themselves in proper relation to the movements necessary to complete the forming operation.

Another object of my invention is to have a forming device of telescoping parts rotatable relative one to the other, and which adjust themselves automatically in proper position while the forming operation is in progress to completion.

20 A further object is to provide a forming device for sheet metal forms having telescoping-rotative parts which will act in sequence and position themselves so as to permit the formation of the objects formed in sequential operations without removing the piece from the forming device until it has been completely formed.

Broadly it is the object of my invention to provide a plunger type drawing and forming tool comprising a male plunger with internal master shapes adapted to force metal discs into the female part of the forming means, elements within the female part comprising a plurality of rotatable telescoping members with helical guiding means to automatically position the members in proper position for the various steps essential in the forming operation, and thereby eliminate the necessity of removing the piece being formed 40 from the device until the forming operation has been completed.

These and other objects will be more specifically pointed out in the specifications and the drawings forming part of this specification, and illustrating a preferred embodiment of my invention.

In the drawings:—

Figure 1 is a side elevation with parts in section showing the device ready to receive a piece of sheet metal for forming.

Figure 2 is a perspective of a form to be made by the device.

Figure 2a is a side elevation of the device showing the first step of forming after shearing the metal disc. 55

Figure 3 is an elevation in section showing another step in the forming operation.

Figure 4 is a side elevation with parts in section showing the position of the parts at the completion of the forming operation. 60

Figure 5 is a plan in section taken on the line 5—5 of Figure 1.

Figure 6 is a plan of one of the telescoping parts having internal helical guiding means.

Figure 7 is an elevation in section taken on the line 7—7 of Figure 6. 65

Figure 8 is a top plan of another telescoping member to which is attached the trip finger.

Figure 9 is a side elevation of the member 70 shown in Figure 8.

Figure 10 is a front elevation of the cam operating the trip.

Figure 11 is a side elevation with part in section of the cam operating the trip. 75

Figure 12 is a plan view of the blank holder.

Figure 13 is a side elevation of the blank holder.

Figures 14 to 17 inclusive are sectional 80 views showing the type of forming device intended for use on a toggle press, and the various positions taken by the parts in the act of forming a metal shell.

A main bolster block 1 consists of a base 1a and an upwardly extending boss 1b having a cavity 1c for retaining the parts of the forming device. The bottom 2 of the cavity has a threaded hole 3, vertical spring retaining pockets 3a, an elongated slot and hole 3b for a cam rod 4, and other holes 3c for piston rods 5. Fixed to the base of the bolster block is a downwardly extending boss 6 with an inner bore 6a to provide a hydraulic cylinder 6b for a piston 6c. 90

A stationary centrally located forming member 7 has a threaded portion 7a for securing it by screwing into the threaded hole provided in the bolster block. A cylindrical portion 7b provides a shoulder 7c for contact 95 100

with the bottom of the cavity in the bolster block. The surface 8 of the cylindrical stud portion provides a bearing for a telescoping member. The forming part of this member 5 in this case has a shape similar to a mushroom. A shoulder 7e on the underside of the mushroom shape of this member acts as a stop and limits the upward movement of a telescoping member. A center hole 7f, the top 10 of which provides a shearing edge for a piercing die, extends through the full length of the stationary member. Blanks pierced in this hole fall through to a pocket 7g and are discharged through an opening 7h provided 15 in the bolster block.

While only two telescoping members have been illustrated, it will readily occur to those skilled in the art to decrease or increase the 20 number of telescoping members, depending upon the contour of the form required. In this case the inner telescoping member has a flange 9 integral with which is a trip finger 9a extending beyond the surface 9b of the flange. The base 9c of the telescoping member is 25 slidable while rotating on the bottom of the cavity. Extending upwardly and integral with the base is a tube 10. On the outer surface of the tube are fixed sections 10a of a multiple helix. The proper angle of the 30 helixes will be determined by the amount of friction necessary to the telescoping of the parts. The upper ends 10b of the helixes are flat and provide a stop for another telescoping member for a certain length of time to 35 permit forming by this other telescoping member. This inner telescoping member is rotatably mounted on the surface 8 of the fixed forming member. It is also rotatably mounted within the other telescoping member. A stop pin 11 fixed in the underside 9c of the flange of the inner telescoping member extends downwardly and is slidable in an 40 annular groove 11b in the bolster block. This pin is acted upon by a compression spring 11c retained within the groove, and the spring in turn reacts against a fixed abutment 11d shown as a pin also within the groove.

The other telescoping member has a sleeve 12 with a hole 12a on the surface of which are 45 extending sections 12b of multiple helixes. The angle of these helixes will correspond to the angle on the first described telescoping member, so that they can come into mesh and slide along each other. This member is slidable vertically on the other telescoping member. The sleeve has two different diameters 12d and 12e, the top edge 12f of the largest of the two diameters providing a shearing edge for excess material of the blank. Integrated with and at the bottom of the sleeve is a flange 13 in which are fixed downwardly extending plunger rods 13a. The rods have heads 13b slidable in the spring pockets 3a and the heads rest on the springs 13c, also 55 confined within the pockets 3a. Other clear-

ance holes 13d are provided in the flange in which piston rods 5 are free to slide. An elongated clearance slot 14 is provided for the cam rod 4. This slot permits downward movement of the cam. 70

The blank holder is a ring 15a with a hole 15b so that it can slide down over the surface 12e of the telescoping member 12. Fixed to the underside 15c of the blank holder are spaced piston rods 5. One of these rods has an elongated notch 15d so that the trip finger 9a will not be interfered with while being moved by the cam. 75

The outer surface of the ring is provided with two different diameters 15e and 15f. The diameter 15f is slidable within a hole 16 of a blanking die which will be later explained. The other diameter 15e provides a ledge 15g which acts as a stop to limit the upward movement of the blank holder. As 80 previously stated, the piston is rigidly secured to the piston rods at 15h.

A counterbore 16 is provided in the bolster block for securing therein a blanking die 17 with a central opening 17a having a shearing edge 17b. A shoulder 17c beneath the shearing edge is provided as stop means against which the ledge 15g comes in contact to limit the upward movement of the blank holder. The inner surface 17d of the hole providing 85 the cutting edge acts as a guide for the blank holder and also as a punch. The die remains stationary at all times. 95

The cam rod 4 has a hole 18 for a spring 18a. A plug 18b with a hole 18c slidably retains a plunger shank 19 with a head 19a that compresses the spring whenever the end 19b of the plunger shank bears on the piston. The plug is fixed in the hole in the end of the rod and prevents the spring from ejecting the 100 plunger. The upper end 19c has a rectangular extension 20, one face 20a being vertical and parallel to the central axis of the rod. A sloping surface 20b connects the vertical face with the rod and acts as a cam surface to 105 rotate the inner telescoping member by contact with the trip on this said inner telescoping member. At the top of the cam rod a tapped hole is provided for an adjusting screw 21 having a lock nut 21a to hold it in a 110 set position. The cam rod is slidably mounted in the hole 3b in the bolster block. It is moved downwardly by the blank holder and upwardly by the piston that actuates the blank holder. 115

The plunger or male forming member when assembled is rigidly attached to the ram of a suitable press (not shown). It comprises a punch holder 22 having a circular hub 22a, with a counterbore 22b and a central hole 22c. Integral with the hub is a flange 23 also provided with a counterbore which centrally locates a combined punch and forming member which will be later explained. Holes 24 are provided for screws which secure the 120 125 130

punch and forming member to the flange. Other holes 25 are provided for rods 26 that are slidably retained therein. These rods are rigidly attached to a plate 27 that is slidably mounted within the counterbore 22b. On the upper side of the plate is a stud 27a that is rigidly attached to the plate. This stud comes into contact with a part of the press ram and causes the plate with its rods to move downward and push on a stripper.

The combination punch and forming member 28 is rigidly secured in the counterbore 29 by screws in its flange portion 28a. An extending boss 30 is cylindrical in shape and is free to slide in the hole in the blank holder. The bottom edge 30a is constructed to provide a shearing edge for blanks to be cut from sheet material. The upper end 30b is counterbored to receive a plunger to be described. Another hole 30c is provided as a bearing for the plunger and connects the counterbore with the lower end 30d of the plunger. The lower end will be machined to the outside contour of a particular form which, in this case, is shown at 31, and consists of concentric rings 31a and 31b, joined together by a shoulder 31c and terminating in a cone-shaped top 31d.

The ejecting plunger 32 has a sleeve-like portion 32a slidably mounted in the hole 30c. Integral with the sleeve-like portion is a hub 32b that is slidably mounted in the counterbore in the upper end of the punch. In the center of the plunger there is a hole 32c for slidably retaining a piercing punch 33. A shoulder 32d limits the movement of the ejecting plunger when it comes into contact with the base of the counterbore.

The piercing punch has a shank 33a which is pressed and fixed within the hole 22c provided in the punch holder. The top end 33b of the shank abuts against a shoulder 34 provided in the hole 22c. The lower end 33c of the shank is slidably mounted in the hole 30c in the ejecting plunger. The bottom end 33d is the piercing end of the punch.

A brake shoe 37 rigidly fastened to a rod 37a bears against the outer surface of the flange of the inner telescoping member. The rod 37a is slidably mounted in a hole 38 in the boss of the bolster block. The end 38a is threaded for adjusting nuts 38b that bear against a compression spring 39 slidably mounted on the end of the rod. A U-shaped band 40 is rigidly attached to the boss of the bolster block and the inner side 40a acts as an abutment for the spring which is always holding the brake shoe in contact with the flange on the telescoping member.

An alternative type of forming tool which is intended for use on a toggle press will now be described. In this forming tool the operation and the parts are inverted when compared with respect to the tool just described. It consists of a bolster block 41 having a hole

low boss 41a and a flange 41b. Internally within the hollow boss is mounted a female die block 42 having a central hole 42a with varying diameters 42b, 42c and 42d. The two upper diameters terminate in beveled shoulders 43 and 43a. A top edge 43b of the largest diameter provides a shearing edge.

The punch, as in the first described device, will be attached to a toggle actuated ram of a toggle press (not shown). Rigidly attached to the movable part of the ram is a plate 44 having a hole 44a therein. On the top 44b, fixedly attached, is a beveled cam member 44c. On the underside 44d is fixed a flange 45 integral with a cylinder 45a extending from the flange. A tapped hole 45b for an air inlet tube 45c is provided on the side of the cylinder. A disc piston 46 is slidably mounted within the cylinder, and has a hole 46a that bears and is slidable on the outer surface of one forming member to be explained.

The forming member 47 is rigidly fastened in the flange 45. It has a beveled edge 47a and a central hole 47b. This forming member performs the shearing of the disc and the first step in the forming of a shell, as shown. Another forming member 48 is tubular in shape, having its bottom edge 48a beveled to match the beveled shoulder in the female die. This member is slidably mounted in the first forming member. At the top 48b there is an internal helix 48c. An opening 48d extends through the entire length of this forming member. This member performs the second step in the forming operation. A vertical shaft 49 is slidably mounted in the opening 48c. The upper end 49a of this shaft is smaller in diameter and provides a shoulder 49b against which a sleeve 50 rests. This sleeve is fixed on the shaft. On the outer surface and at the lower end 50a there is a helix 50b which can mesh with the other helix on the second forming member.

Slidably mounted on the sleeve is a collar 51 with an extending finger 52 with a sloping surface 52a. It is seated on the top edge 52b of the second forming member, as shown in Figure 14. This collar rotates the sleeve by means of a key 54 fixed in the sleeve and meshing in a slot 55 in the collar and brings the two helixes into position so that the sleeve and the second forming member can telescope upon each other.

Operation of first forming tool

Figure 1 shows the position of all parts at the beginning of the forming operation and a sheet of metal, indicated in dotted lines, is shown on top of the die. The blank holder, telescoping member and the cam are in the extreme upper positions. The telescoping member 12 is resting on the flat tops of the helixes of the other telescoping member. The punch and plunger part of the forming tool move continuously during the forming operation.

As the punch and plunger come down, the metal will be clamped between the surface 35 of the punch and the top surface 35a of the blank holder. While moving down, the punch passes through the die and presses out a disc of metal. This disc is kept clamped during the entire forming operation.

The first forming operation is accomplished by forcing the metal down over the top of the telescoping member 12 and up into the largest diameter of the plunger (see Fig. 2a). While this operation is taking place, the blank holder pushes the cam rod downward and the cam will rotate the inner telescoping member into position so that the helixes on the members can engage. When the helixes engage the telescoping member 12 will slide down over the inner telescoping member. The inner telescoping member will rotate by the action of the continually applied pressure of the plunger. While the member 12 is sliding down over the inner telescoping member, the metal will be forced down over the top of the fixed forming member, as shown in Figure 3.

The ejecting plunger will then come into contact with the top of the form and hold it for the piercing operation. Further movement forces the metal up into the female form and at the same time the excess material 36 will be sheared off around the circle 36a, because the plunger forces the metal over the shearing edge 12f of the telescoping member 12. The hole 36b will also be pierced, and the parts will then be in the position as shown in Figure 4.

The plunger will then return upward. Air is admitted to the hydraulic cylinder and causes the piston to rise. With the rising of the piston the blank holder moves towards its initial position. The cam is also moved up by the piston. Pressure having been taken off of the telescoping member 12, the springs 13c react and force it to its uppermost position. Simultaneously the spring in the slot 11b will also react on the pin 11 and rotate the inner telescoping member until it will be in the position with the telescoping member 12 resting on the flat tops of the helixes on the inner telescoping member.

The form will rise with the plunger, and when it has reached a certain point in upward travel, the stud 27a will come in contact with a fixed member on the press ram. The plate 55 with its rods will push on the ejecting plunger, which in turn will then push on the form and eject it from the plunger. All parts will then be in position, as shown in Figure 1.

60 Operation of the toggle press forming tool

A sheet of metal is laid on top of the die. The punch is moved downward and the disc 46 securely clamps the metal to the top of the die. A disc of metal is sheared by the first forming member and is then pushed into

the largest diameter of the die, as shown in Figure 15. The forming member 48 then pushes the partly formed shell into the next smaller diameter of the die, as shown in Figure 16. When the plunger reaches this position, the finger will have come in contact with the cam, which will rotate the collar and the sleeve so that the helixes can mesh and allow the shaft to push the shell down farther into the die, as shown in Figure 17. It will be understood from the description that the sleeve cannot go down into the forming member until the collar has rotated the helixes into position for meshing.

When the plunger returns upward the collar will rotate the sleeve up out of the forming member where it will again seat itself on the top of the forming member. Further upward movement brings the parts up out of the die, and when they are out air is admitted into the cylinder and the disc will return to the position as shown in Figure 14.

Having thus described my invention, what I claim as new and desire to secure by Letters Patent, is:

1. In sheet forming apparatus comprising a forming die member and a forming punch member, each having elements of successively decreasing cross dimensions, elements of one member successively coacting with respective elements of the other member by relative recession of the elements of one member incident to relative approach of the members, and frictionally coacting means controlling the relative recession of the elements initially having a positive coaction to prevent the relative recession, means operated incident to relative approach of the members, acting on the controlling means to initiate the frictional coaction, said controlling means being operative independently of the initiating means after initiation of its frictional coaction, and means to return the elements and the initiating means to their initial relative positions upon relative recession of said die and punch members.

2. Apparatus as set forth in claim 1 in which the means to return the elements comprises a spring, and the means to return the initiating means comprises a fluid actuated plunger.

3. Apparatus as set forth in claim 1 in which the recession controlling means comprises an element rotatable relatively to one of the receding elements, said rotatable element and said receding element having mutually engaging helical portions the friction between which, in conjunction with the friction of rotation of the rotatable element, provide the control of recession of said receding element, and in which the initiating means comprises an extension on said rotatable element and a cam engaging said extension.

4. Apparatus as set forth in claim 1 in which the recession controlling means com-

- prises an element rotatable relatively to one of the receding elements, said rotatable element and said receding element having mutually engaging helical portions the friction between which, in conjunction with the friction of rotation of the rotatable element, provide the control of recession of said receding element, and in which the initiating means comprises an extension on said rotatable element 5 and a cam engaging said extension, and in which the returning means comprises a spring acting upon said rotatable element substantially in the plane of its rotation.
5. Apparatus as set forth in claim 1 in which the recession controlling means comprises an element rotatable relatively to one of the receding elements, said rotatable element and said receding element having mutually engaging helical portions the friction between which, in conjunction with the friction of rotation of the rotatable element, provide the control of recession of said receding element, and in which the initiating means comprises an extension on said rotatable element 10 and a cam engaging said extension, and in which the returning means comprises a spring acting on the rotatable element substantially in a plane of its rotation, and a second spring acting on the receding element in direction opposite to its recession, and in which the means to return the initiating means comprises a fluid actuated plunger acting on the cam.
6. Apparatus as set forth in claim 1 in which the recession controlling means comprises an element rotatable relatively to one of the receding elements, said rotatable element and said receding element having mutually engaging helical portions the friction between which, in conjunction with the friction of rotation of the rotatable element, provide the control of recession of said receding element, and in which the initiating means comprises an extension on said rotatable element 15 and a cam engaging said extension, and in which the returning means comprises a spring acting on the receding element in direction opposite to its recession.
7. Apparatus as set forth in claim 1 in which the recession controlling means comprises an element rotatable relatively to one of the receding elements, said rotatable element and said receding element having mutually engaging helical portions the friction between which, in conjunction with the friction of rotation of the rotatable element, provide the control of recession of said receding element, and in which the initiating means comprises an extension on said rotatable element 20 and a cam engaging said extension, and in which the means returning the rotatable element and the receding element comprises a spring, and the means to return the initiating means comprises a fluid actuated plunger acting on the cam.
8. Apparatus as set forth in claim 1 in which the recession controlling means comprises an element rotatable relatively to one of the receding elements, said rotatable element and said receding element having mutually engaging helical portions the friction between which, in conjunction with the friction of rotation of the rotatable element, provide the control of recession of said receding element, and in which the initiating means comprises an extension on said rotatable element 25 and a cam engaging said extension, and in which the means returning the rotatable element and the receding element comprises a spring acting on the rotatable element substantially in a plane of its rotation, and a second spring acting on the receding element in direction opposite to its recession.
9. Apparatus as set forth in claim 1 in which the forming punch member has the relatively receding elements and is surrounded by a blanking die, and the forming die member is exteriorly formed as a blanking punch coacting with the blanking die prior to the first forming coaction, and including a blank holder in the blanking die which recedes in blank holding coaction with the forming die and by its recession operates the initiating means to initiate the frictional coaction, and is returned to initial position by the means that returns the initiating means.
10. Apparatus as set forth in claim 1 in which the recession controlling means comprises an element rotatable relatively to one of the receding elements, said rotatable element and said receding element having mutually engaging helical portions the friction between which, in conjunction with the friction of rotation of the rotatable element, provide the control of recession of the receding element, and including a brake in frictional contact with said rotatable element, means having a yielding pressure on said brake to hold it in said contact, and means for adjusting said pressure.
11. Apparatus as set forth in claim 1 in which the initiating means comprises a cam having means for adjusting its effective length and operating means advanced incident to relative approach of the members, engaging one end of the cam, and in which the means for returning the initiating means comprises a fluid-actuated plunger connected to and returning said operating means from its advanced position, said cam having its opposite end yielding and engaged by said plunger for return of the cam, said yielding end permitting the cam to maintain contact with the plunger and said operating means at various adjustments of its effective length.
12. In sheet forming apparatus, a fixed central forming punch element, an element rotatable around said punch, a forming

punch element surrounding and adapted to recede relative to said central punch element and rotatable element, said surrounding punch element and said rotatable element having mutually engaging helical portions controlling recession of the forming element by rotation of the rotatable element and initially in unmeshed engagement, positively preventing recession of said forming element, a forming die having interior elements to coact, respectively, with said central punch element and with said surrounding punch element upon relative approach of the die and the punch elements, and means for initially 10 rotating said surrounding punch element to mesh the helical portions, comprising an extension from the rotatable element, and cam means actuated by the forming die and engaging said extension, said rotatable element 15 carrying its extension free of said cam upon further rotation with its helical portion in mesh with the helical portion of the surrounding punch element receding in coaction 20 with the respective die element.

13. Apparatus as set forth in claim 12 in which the surrounding punch element initially extends past the central punch element to coact with its respective die element previous to coaction of the central punch element 70 with its respective die element.

14. Apparatus as set forth in claim 12 in which the punch elements are surrounded by a blanking die, and the forming die is exteriorly formed as a blanking punch coacting 75 with the blanking die prior to the first forming coaction, and including a blank holder in the blanking die which recedes in blank holding coaction with the forming die and constitutes a transmission element by means 80 of which the forming die actuates the cam means, and the surrounding punch element initially extending past the central punch element to effect the first forming coaction, 85 previous to coaction of the central punch element with its respective die element.
